UNITED STATES PATENT OFFICE.

ELLSWORTH B. A. ZWOYER AND ROLLAND A. ZWOYER, OF PERTH AMBOY, NEW JERSEY, ASSIGNORS TO THE ZWOYER FUEL COMPANY, A CORPORATION OF NEW JERSEY.

MACHINE FOR MAKING BRIQUETTES.

1,152,468.

Specification of Letters Patent.

Patented Sept. 7, 1915.

Application filed October 26, 1908. Serial No. 459,576.

To all whom it may concern:

Be it known that we, ELLSWORTH B. A. ZWOYER and ROLLAND A. ZWOYER, citizens of the United States, and residents of Perth Amboy, county of Union, and State of New Jersey, have made a new and useful Invention in Machines for Making Briquettes, of which the following is a specification.

Our invention is directed particularly to improvements upon briquette-making machines, such as are disclosed in prior U. S. patents granted to us as follows—No. 667,050, of Jan. 29th, 1901; No. 676,484, of June 18th, 1901, and No. 718,943, of Jan. 6th, 1903, in which briquettes are molded or formed between two tangentially arranged molding rolls or drums provided with briquette forming pockets, and it has for its objects, first, to so construct rolls or drums of this nature that the forming pockets shall all be identically alike in both rolls, and the adjoining walls of the several pockets shall be provided with the sharpest possible cutting edges, all so located in the faces of both rolls that when the two are rotated in the process of forming briquettes there will be no possibility of compressing any of the material between the adjoining edges of the pockets in the rolls in such manner as to form ragged edges or flanges on the briquettes, or to cause any unnecessary waste of energy in the application of power in thus forming or compressing briquettes. Second, to provide the briquette making rolls of such a machine with a novel shape or conformation of pocket adapted to make a briquette having great strength and durability and of equal density throughout its mass. Third, to provide means for adjustment between the rolls whereby in the event of lost motion due to wear of the driving gear or other parts of the apparatus said rolls may be so adjusted that the tangential edges of the pockets shall always be in exact alinement with each other at the points of highest compression; that is to say, they shall be in exact alinement with each other when they are in a plane passing through them and through the mathematical axes of the two shafts which support the forming rolls. Fourth, to provide novel means for feeding the material forward to the rolls and in such manner that it will be equally distributed over the top surfaces thereof so as to produce the best

possible effects and prevent any possibility of causing the rolls to exert greater pressure upon the material as it advances therethrough upon any one portion thereof.

Our invention will be fully understood by referring to the accompanying drawings, in which,

Figure 1 is a side elevational view of a briquette making machine embodying our several improvements, in so far as they relate to the machine. Fig. 2 is a plan view thereof as seen looking at Fig. 1 from the top toward the bottom of the drawings. Figs. 3, 4, 5, 6 and 7 are detail views of the means for radially adjusting the two shafts which support the briquette making rolls in such manner as to enable one to always maintain the adjacent knife edges of the pockets in direct alinement with each other and in the same plane as the mathematical axes of their supporting shafts. Fig. 8 is an edge view illustrating the nature of the briquette making pockets of the rolls and the manner of constructing the same; and, Fig. 9 is a sectional view of the same taken on the line X—X Fig. 8 and as seen looking therewith from right to left in the direction of the arrows. Figs. 10 and 11 are plan and edge views of one of our novel briquettes as constructed by our improved briquette making machine.

In the manufacture of briquette making machines of the roller or drum type in which the briquette forming pockets are located in the surfaces thereof, it is important, as pointed out in the before-mentioned patents, that these pockets shall all be identical duplicates and shall be so related to each other on both rolls or drums that as the material is advanced and the briquettes are completed there will be the nicest adjustment of the parts so as to effect a clean cut product without any possibility of exerting any compressive action upon the material, other than that which is required to form the completed briquettes in the pockets, it being stated in said patents that often times any imperfection in the edges of the pockets causes not only an imperfect briquette, but necessarily enforces a waste of energy by the compression of material between the edges of the pockets.

It is a matter of common knowledge that in the manufacture of briquette making rolls

it is not possible to cast two briquette making rolls in such manner as to obtain the relations of the pockets on their surfaces in the manner hereinbefore stated. The improved briquette making rolls disclosed in the before-mentioned patents were designed to overcome this objection, so far as possible, and it was with the intention of effecting more perfect rolls that this feature of the present invention was designed. We have also ascertained that in the use of briquette making rolls like those disclosed in a prior patent No. 718,043, granted to E. B. A. Zweyer, where the material is fed forward directly to the rolls from the hopper, said material from which the briquettes are made frequently clogs or accumulates at the lower inner edges of the hopper to such an extent as to prevent the material from falling into those pockets at the extreme ends of the rolls, thereby putting out of commission such pockets and sometimes, also by reason of such accumulation, causing the forming of imperfect briquettes in adjoining sets of pockets, and for the purpose of overcoming this objectionable feature we have devised means for equally distributing the feed of the material over the top surfaces of the rolls so that perfect briquettes are always produced in all of the pockets.

In U. S. Patent No. 667,050 is disclosed a form of briquette which resulted from the use of the machine illustrated in that patent. This form of briquette, however, does not possess the required density nor strength, being somewhat fragile, and by reason of the structural nature of the forming cups or pockets disclosed in said patent the best results are not had in transportation and combustion with such a briquette. The present improvement is designed also to overcome this objectionable feature.

Referring now to the drawings in detail in all of which like numerals of reference represent like or equivalent parts wherever used, and first to Figs. 1 and 2, 1, 1, 1 represent the base or support of the machine and 2 the usual metallic frame therefor; 3 being a driving shaft journaled at one end of the frame and provided with the usual driving pulley. This shaft is connected in turn by a clutch 4 with a short shaft 5 journaled also in the frame and carrying a pinion 6 which meshes with a gear-wheel 7 located at one end of one of two drum carrying shafts 8, 8, for supporting and rotating the briquette forming rolls or drums 9, 9, said shafting being provided, as shown, with well known means, in the nature of adjusting screws and worm and gear mechanism, for adjusting the relative positions of the two rolls or drums 9, 9.

10 is a hopper for feeding the material forward to the briquette forming rolls or drums and 11 is a feeding tube or pipe having

the shape or conformation of a truncated pyramid, the same constituting means for feeding the material forward to the rolls in such manner as to equally distribute it over the top surfaces thereof. This feeding tube is supported with its lower edges practically out of mechanical contact with the hopper 9 and its structural arrangement is such that by no possibility can there be formed any deposit of the material as it descends through the tube, either thereon or on the hopper 10, such an arrangement making it absolutely sure, as we have ascertained in practice, that the material will be evenly distributed over the exposed faces of both rolls at all times, thereby making it possible to utilize all of the briquette forming pockets on both rolls and to always produce absolutely perfect briquettes in all of such pockets. For the purpose of effecting this result with the best possible advantage we prefer to make the inner conveying surface of the tube of greater width than the length of the operative parts of the briquette forming rolls; that is to say, of such cross sectional area that by no possibility can there be an accumulation of dust on the inner surface of the tube 11 which shall project over the working faces of the rolls 9, 9, thus assuring at all times the fact that as the material descends it will absolutely fill all of the briquette forming pockets. On the pair of rolls 9, 9, there are two flanges 9^a, 9^a, extending beyond the ends of the roll. They are shown as located on one of the rolls. The inner surfaces of these flanges are flush with the outer edge of the opposite roll, as shown in Fig. 2. Their inner surfaces are also flush with the inner lower surfaces of the hopper 10, as shown in Figs. 1 and 2. These flanges come in contact with the material resting on the rolls and extending up into the hopper, and serve to drag the material into the rolls adjacent to the hopper, thus feeding the material to the pockets which are located near the ends of the rolls, and assuring a proper supply of material to these pockets.

12, 12 represent intermeshing gear-wheels carried by the two shafts, 8, 8, one of said gear-wheels being permanently keyed to one of the shafts and the other adjustably keyed to the other shaft by the structural device illustrated in Figs. 3 to 7 inclusive, in which 13 represents a lug or extension on one face of the gear-wheel 12.

14 is a sleeve provided with an enlarged head 15 and two extensions 16, 16 having adjusting screws 17, 17, the arrangement being such that said sleeve may be keyed directly to the shaft 8 by a spline and key 18 with the gear-wheel 12 surrounding said sleeve and the lug or extension 13 projecting between the inner ends of the adjusting screws 17, 17. It will be apparent that when

5 this gear-wheel and its adjusting sleeve are thus keyed to one of the shafts 8 the angular relation of that gear-wheel to the other gear-wheel may be varied by shifting the adjusting screws 17, 17 at will, these adjustable devices constituting means for varying the angular relation of the rolls or drums 9, 9, as will be apparent on inspection of the drawings.

10 In Figs. 8 and 9 we have illustrated the detail structure of the rolls or drums and the manner of constructing the same, each drum consisting of a series of hollow circular disks 19 of the same general nature as 15 those disclosed in the before-mentioned U. S. Patent No. 718,043, except that in the present instance said disks are first cast in the manner shown in Fig. 8 with a series of complete integral pockets 20 in their outer or 20 edge faces having each the conformation of the frustum of a pyramid with a rounded apex or top and rectangular base. After they are thus cast with relatively heavy marginal surfaces 21, 21 upon the side faces of 25 the disks, they are then placed in a planer and these surfaces planed off so that the lateral edges of the pockets on both sides assume a knife-edge conformation. The edges between the pockets are dressed with a tool 30 to the sharpest possible condition. These disks being each provided with a spline 22 are then grouped and bolted together upon the shafts 8 in the same manner as disclosed in the above-mentioned patents so that all 35 of the edges of the pockets are in alinement with each other, both tangentially and radially, and by this means we are enabled to produce a roll or drum in which the completed pockets are absolute duplicates of 40 each other throughout the entire surfaces of the rolls and are located in such relation to each other that the nicest cutting effect is had in the dividing up of the material as it is fed forward during the process of the 45 making of briquettes. When these disks are assembled on the shafts 8, 8 the edges of the pockets are all in alinement in planes in each direction. It will also be apparent that by reason of the adjustable means illustrated in detail in Figs. 3 to 7 inclusive the nicest adjustment of the rolls may be effected so as to bring about the alinement of the 50 knife edges of the several pockets of the two rolls as these edges pass by each other at the 55 elemental or tangential line.

60 We have ascertained that in the use of such an improved briquette making machine we are enabled to produce a briquette like that illustrated in Figs. 10 and 11 of the drawings, each having the cleanest possible surfaces and edges and one in which the density is practically constant throughout its mass, and also of such structural form that the greatest possible strength is given thereto, thus making it not only an article which

will permit of transportation without undue breakage, but also one which, as we have ascertained in practice, gives a maximum combustion effect. The form of this briquette is, as will be obvious on inspection of Figs. 70 9 and 10, that of the frustums of two pyramids having their rectangular bases integrally united, while the frustum ends thereof are slightly rounded.

75 We do not limit our invention to the details of construction illustrated in the accompanying drawings and hereinbefore described, as a number of the features thereof may be materially departed from and still come within the scope of our claims herein-after. To illustrate, various modified means might be devised for effecting the relative axial adjustment of the rolls or drums 9, 9, from that illustrated in Figs. 3 to 7 inclusive, and other means than the tube 11 might 80 be utilized for distributing the material as it is fed forward in the manner described, and our claims are of the most generic nature as to these features. We believe it is 85 also broadly new with us to construct a 90 briquette making roll or drum composed of closely associated disks having complete pockets in the edge face of each of the disks, and that it is also new to provide a briquette 95 making machine of the drum type with a 100 pyramidal shaped feeding means in the nature of the frustum of a pyramid, the base of which is of greater width than the length of the rolls, whereby all of the briquette forming pockets will be filled at all times 105 with the proper amount of material to construct perfect briquettes when the machine is in operation.

Having thus described our invention what 110 we claim and desire to secure by Letters Patent of the United States is—

1. A briquette making roll, composed of a plurality of circular disks, each disk having a single peripheral row of pockets on its edge surface, the pockets being complete in each disk, and there being a like number of pockets in each disk, each pocket extending entirely across the disk, and producing a sharp cutting edge in conjunction with the adjacent pocket on the abutting disk. 115

2. A briquette making machine provided with two forming rolls composed of disks having complete or integral pockets in the outer face of each disk and all supported upon parallel intergeared shafts; in combination with means for varying the angular relation of the surfaces of the rolls, substantially as described. 120

3. In a briquette making machine two forming rolls having an equal number of like pockets on their faces, the horizontal and vertical edges of which register accurately during operation; in combination with means for varying the angular relation of the rolls so that the horizontally disposed 125 130

cutting edges shall always be in actual elemental contact when they pass each other, whereby all of the pressure which the two rolls exert is utilized in effecting perfect briquettes, substantially as described.

4. In a briquette making machine a pair of briquette forming rolls having like briquette forming pockets in their faces; a hopper therefor; a pipe for conveying the material from a source of supply to the hopper, said pipe having a smaller internal diameter at its upper end than the length of the forming rolls, its lower end having an internal diameter of greater length than the forming rolls, whereby the material is distributed equally upon the surface of such rolls, substantially as described.

5. A briquette making machine, having two briquette making rolls, each having pockets each of the shape of a truncated pyramid.

6. A briquette making machine, having two briquette making rolls, each having pockets each of the shape of a truncated pyramid with a rectangular base.

7. A briquette making machine, having two briquette making rolls, each having

pockets each of the shape of a truncated pyramid with the truncated end rounded.

8. A briquette making machine, having two briquette making rolls, each having pockets each of the shape of a truncated pyramid with a rectangular base, and with the truncated end rounded.

9. A briquette making machine, having two briquette making rolls, each having pockets each of the shape of a truncated pyramid, with sides bearing a relation of approximately ninety degrees to one another, and with a rectangular base.

10. A briquette making machine, having two briquette making rolls, each having pockets each the shape of a truncated pyramid with a rectangular base and rounded corners.

In testimony whereof we have hereunto signed our names to this specification in the presence of two subscribing witnesses.

ELLSWORTH B. A. ZWOYER.
ROLLAND A. ZWOYER.
